(57) **CLAIM**

The ornamental design for a bicycle rack as shown and described.

DESCRIPTION

FIG. 1 is a top front perspective view of the bicycle rack according to the new design.

FIG. 2 is a bottom front perspective view of the bicycle rack shown in FIG. 1.

FIG. 3 is a top rear perspective view of the bicycle rack shown in FIG. 1.

FIG. 4 is a bottom rear perspective view of the bicycle rack shown in FIG. 1.

FIG. 5 is a right side elevation view of the bicycle rack shown in FIG. 1.

FIG. 6 is a left side elevation view of the bicycle rack shown in FIG. 1.

FIG. 7 is a rear elevation view of the bicycle rack shown in FIG. 1.

FIG. 8 is a front elevation view of the bicycle rack shown in FIG. 1.

FIG. 9 is a top plan view of the bicycle rack shown in FIG. 1; and,

FIG. 10 is a bottom plan view of the bicycle rack shown in FIG. 1.

The broken lines in the drawings illustrate portions of the bicycle rack that form no part of the claimed design.

1 Claim, 10 Drawing Sheets
